UNITED STATES PATENT OFFICE.

HENRY W. SCATTERGOOD, OF PHILADELPHIA, PENNSYLVANIA.

DESIGN FOR A MUCILAGE-BOTTLE.

SPECIFICATION forming part of Design No. 34,061, dated February 12, 1901.

Application filed January 16, 1901. Serial No. 43,542. Term of patent 14 years.

To all whom it may concern:

Be it known that I, HENRY W. SCATTERGOOD, a citizen of the United States, residing at Philadelphia, in the county of Philadelphia and State of Pennsylvania, have invented and produced a certain new and original Design for Mucilage-Bottles, of which the following is a full, clear, and exact description.

This invention is in the nature of a mucilage-bottle of novel construction for use for packing, storing, and transportation purposes and also for use upon the consumer's desk or elsewhere.

In the accompanying drawings, forming part of this specification, and in the two figures of which like parts are similarly designated, Figure 1 is a perspective view, and Fig. 2 is a vertical central section, of a mucilage-bottle embodying my design.

As shown in the drawings, the leading or

material feature of my design is a step-like gallery surrounding the neck or mouth of the bottle. This step-like gallery comprises the circular laterally-projecting portion *a*, immediately next to and surrounding the neck *b*, and the upright wall *c*, below the portion *a* and above the substantially horizontal portion *d*, all of these parts rising from the body *e* of the bottle. ²⁵

Having thus described my invention, what I claim as new, and desire to secure by Letters Patent, is—

The design for a mucilage-bottle, substantially as shown and described.

In testimony whereof I have hereunto set my hand this 15th day of January, A. D. 1901.

HENRY W. SCATTERGOOD.
